UNITED STATES PATENT OFFICE.

GEORGE W. KISINGER, OF DANVILLE, ILLINOIS, ASSIGNOR OF ONE-HALF
TO FRANKLIN P. KISINGER, OF SAME PLACE.

REVERSIBLE REFLECTOR.

SPECIFICATION forming part of Letters Patent No. 326,041, dated September 8, 1885.

Application filed December 9, 1884. (No model.)

To all whom it may concern:

Be it known that I, GEORGE W. KISINGER, a citizen of the United States, residing at Danville, in the county of Vermillion and State of Illinois, have invented certain new and useful Improvements in Reversible Reflectors; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 My invention has relation to reflectors for lamps and the like, and more particularly to reversible reflectors, and its object is to provide a reflector that can be used in one position to reflect the light down around the lamp, 20 and by reversing the reflector—that is to say, turning it upside down—the light will be reflected radially outward and around the room; and to these ends the novelty consists in a reflector both sides of which are provided with 25 polished or reflecting surfaces, as will be hereinafter more fully set forth.

In the accompanying drawings, the same letters of reference indicate the same parts of the invention.

30 Figure 1 is an elevation of the top of a lamp and shade, showing the various positions in which my improved reflector may be used. Fig. 2 is a perspective view of the standard and reflector adjusted sidewise, and Fig. 3 is 35 a plan view of the arm D and yoke E.

A is the cap or burner of an ordinary lamp, provided with a shade, B.

C is a wire standard, the base-arm D of which terminates in a yoke, E.

F is an adjustable cross-arm secured to the 40 standard C by a screw-clamp, G, which has a fork, H, to support the reflector K. This reflector is provided with a central opening, P, through which the shade B passes, and around the opening P is a collar, S, provided with a 45 flange, T. It will thus be seen that the fork H may be slipped over the collar S to support the reflector, which will be held in place by the flange on the collar. Both sides of this reflector K are made of reflecting material, and as shown in elevation in Fig. 1 the light is reflected downward, and as shown in dotted lines the reflector is reversed, and consequently the light radiated by the reflector around the room. The dotted lines on the 55 lower part of the standard in Fig. 1 show the manner of adjusting it as a side reflector, to throw the light all in one direction.

Having thus fully described my invention, what I claim as new and useful, and desire to 60 secure by Letters Patent of the United States, is—

The reflector K, having reflecting-surfaces on both sides, and provided with central opening P, collar S, and flange T, in combination 65 with the standard D, and the adjustable cross-arm F, having forked end H, as and for the purpose set forth.

In testimony whereof I affix my signature in presence of two witnesses.

GEORGE W. KISINGER.
